COVERED SERVING DISH

Willis Allison Stageberg, Minneapolis, Minn., assignor to
Plastics, Inc., St. Paul, Minn.

Filed Nov. 22, 1961, Ser. No. 67,656

Term of patent 14 years

(Cl. D44—15)

FIG. 1

FIG. 2

FIG. 3

FIG. 4

FIG. 5

FIG. 6

FIG. 7

FIGURE 1 is a top plan view of a covered serving dish, showing my new design;

FIGURE 2 is an end elevational view of the same;

FIGURE 3 is a side elevational view of the same;

FIGURE 4 is a top plan view of the lower portion of the same;

FIGURE 5 is a bottom plan view of the top portion of the same;

FIGURE 6 is a side elevational view of the same with the bottom section telescoped into the inverted top section thereof and

FIGURE 7 is an end elevational view of the same in the relation shown in FIGURE 6.

The essential features of my design reside in the cover member having the specific configuration shown.

I claim:

The ornamental design for a covered serving dish, as shown and described.
